GARMENT

Benjamin Cahn, Far Rockaway, N. Y.

Application January 30, 1935, Serial No. 4,039

2 Claims. (Cl. 2-80)

This invention relates to improvements in garments.

One of the several objects of the invention is to provide a garment of the shoulder strap type 5 wherein a single strap serves the two-fold purpose to suspend the garment from the shoulders of a wearer and to act as a belt.

Another feature resides in a garment wherein a single strap and its association with a garment 10 acts to facilitate adjustment of the garment to the body of a wearer.

A further object of the invention is the provision of a suspender type garment in which the free ends of the suspender straps are crossed 15 at the back and brought around to the front of the garment at the waist portion thereof for the convenience of tying and which is easily accessible particularly for children when the invention is embodied in children's garments.

20 A still further object of the invention is the provision of a suspender type garment which eliminates the use of buttons, buckles, clasps, and other like fastening devices for securing the strap in an adjusted position, and which are a source 25 of concern due to loss caused by strains imparted thereto by the natural body movements of a wearer.

With these and other objects in view, the invention resides in the certain novel construction, 30 combination and arrangement of parts, the essential features of which are hereinafter fully described, are particularly pointed out in the appended claims, and illustrated in the accompanying drawing, in which:

35 Figure 1 is a perspective view of my improved garment upon a wearer and looking at the front thereof.

Figure 2 is a similar view but looking at the rear.

40 Figure 3 is a side elevational view.

Figure 4 is a front elevational view of the garment per se with parts broken away in section.

45 Figure 5 is a rear elevational view of the garment per se with parts broken away.

Figure 6 is an enlarged detail vertical sectional view through the hem at the neck portion of the garment.

50 Referring to the drawing by reference characters, the numeral 10 designates my improved garment in its entirety and which includes a lower garment part 11 in the style of "shorts", although I do not wish to restrict myself to this particular style of garment part, as the same may be in the 55 form of a dress, bathing trunk, trousers or the

like. Extending upwardly from the front of the lower garment part 11 is an upper garment part 12 which is open at the sides and back. The side edges of the upper garment part 12 are shaped so as to snugly conform to the curvature or contour 5 of the body of a wearer, and the top edge is provided with a hem 13. The top of the upper garment part 12 is narrower than the remainder portion of the upper garment part and forms the neck line of the garment when in position upon a 10 wearer.

Freely passing through the hem 13 is the intermediate portion of a single strap 14, the end portions of the strap extending rearwardly and crossed as at 15 to provide shoulder straps 16. 15 Loops or eyes 17 are provided at opposite sides of the garment at the waist portion thereof and through which the free ends of the strap respectively pass in a direction from back to front, the free ends being brought around the front of 20 the waist portion of the garment and tied as at 18, thus imparting the appearance of a belt to the front of the garment.

In practice, the garment is donned when in the position shown in Figures 4 and 5, the wearer 25 stepping into the lower garment part 11 and bringing the shoulder straps 16 over the shoulders as shown in Figure 2. After entering the garment in this manner, the wearer pulls upon the free ends of the strap to tension the strap causing 30 a gathering of the upper part of the garment part 12, the tension placed upon the strap being sufficient to effect an adjustment of the garment vertically upon the body of a wearer. After pulling the loose ends of the strap to the desired tension, the same are tied at the front as shown in 35 Figure 1 of the drawing.

The construction of this garment eliminates the necessity of reaching to the rear to effect fastening of the garment upon the body of a 40 wearer and a child with the knowledge of tying a knot may don the garment or remove the same without the aid of an older person.

In the drawing, the lower garment part 11 at the waist portion at the top rear is provided with 45 a hem through which an elastic strap 19 passes and is secured at the ends thereof under tension for causing the rear of the lower garment part to appear gathered and adjustably fit the back of the wearer at the waist line thereof. 50

As before stated, I do not wish to limit myself to the style of garment shown and described, as the invention is equally adaptable to bathing suits, sun suits, beach pajamas and the like.

While I have shown and described what I deem 55

to be the most practical embodiments of my invention, changes and modifications which come within the scope of the appended claims may be resorted to if desired.

5 Having thus described the invention, what I claim as new and desire to secure by Letters Patent of the United States, is:—

- 10 1. A self adjustable garment comprising a lower garment part and an attached upper front garment part, a single strap having its intermediate portion slidably connected to the top of said upper front garment part, the free ends of said strap extending rearwardly and crossed at the back, and loops secured to the waist portion of the garment adjacent the sides thereof through which the respective free ends of said strap pass to facilitate passage of the free ends across the front of the garment and the connection of said free ends at the front.
- 15 20 2. A self adjustable garment comprising a lower garment part and an upper garment part open at the back and connected to said lower garment

part, a hem at the top of the front of said upper garment part, a strap freely passing through said hem, the free ends of said strap extending rearwardly and downwardly in crossed relation at the back to provide shoulder loops above the point of crossing of said strap, and loops adjacent the sides of said garment at the waist portion thereof through which the respective free ends of said strap pass in a direction toward each other at the front of the garment, the meeting ends of said strap being tied together to secure the strap in a tensioned condition when the garment is upon a wearer to cause a gathering of the hem and effect adjustment of the garment to the body of a wearer, a hem provided in the top of the back of said lower garment part, and an elastic strap having its ends fastened under tension at the ends of said last mentioned hem and extending therethrough to effect a gathering of the top of said lower garment part at the rear.
